UNITED STATES PATENT OFFICE.

DANIEL KOPS, OF NEW YORK, N. Y.

APPAREL-CORSET.

1,215,287.

Specification of Letters Patent.

Patented Feb. 6, 1917.

Application filed August 10, 1916. Serial No. 114,090.

To all whom it may concern:

Be it known that I, DANIEL KOPS, a citizen of the United States, residing at the borough of Manhattan, city, county, and State of New York, have invented an Improvement in Apparel-Corsets, of which the following is a specification.

Owing to the lack of sufficient flesh to fill out the frame of the body, thin women have prominent hip bones and very often at the sides of the body there is a marked depression or cavity between the hip bone and the waist line. Ordinarily the corset, as well as other garments worn by such persons, fit more or less closely in these depressions at the sides over the hip bones, resulting in an irregular or unsymmetrical figure.

Now the object of my invention is to overcome this difficulty by providing a corset so constructed that a portion of each body half of which the garment is made, fits over or bridges this depression in the body of the wearer, and the garment made in accordance with this invention will be hereinafter more particularly described.

In the drawings:

Figure 1 is a front elevation of an apparel corset in which my present invention is illustrated.

Fig. 2 is an enlarged elevation of one of the corset body halves.

Fig. 3 is a partial cross section illustrating the manner in which the garment at the sides thereof bridges the depression in the side of the wearer between the hip bone and the waist line, and Fig. 4 is a diagrammatic plan illustrating the form of the gore insert before the parts thereof are connected.

In carrying out this invention, the corset garment made in accordance therewith comprises, as is usual, the corset body halves indicated at 10; in each of these as is also customary, front steels 11 having hooks 12 are provided for securing the parts of the garment together along the front edges thereof, and at the rear, the edge of each corset body half is provided with eyelets 13, so that these edges may be connected by suitable laces 14.

As shown in the drawing, and particularly illustrated in Fig. 2, this garment is provided with suitable stays 15 and 16 placed at appreciable distances from the longitudinal side line thereof, and in other places may be stayed in any suitable manner.

Between the stays 15 and 16, portions of

which are adapted to lie on opposite sides of the hip bone, I employ gore members 17 and 18, the upper gore member 17 being secured at its side edges adjacent the upper portions of the stays 15 and 16, and the lower edge of this upper gore member is preferably convex in outline. The lower side gore member 18 is also secured along its opposite edges adjacent the stay members 15 and 16, and at its upper edge is preferably concave in outline, the concave outline of this lower side gore member corresponding generally with the lower convex edge of the upper side gore member 17 but being of a different curvature as indicated in Fig. 4. These edges are made to overlap, the upper edge of the lower member, preferably overlapping the lower edge of the upper member along which they are suitably secured by lines of sewing or otherwise, to form a curved reinforcing strip, as indicated at 19. This construction, constricting the garment immediately above the waist line and leaving the same free below the waist line to fit over the hip bone of the wearer, causes a portion of the side gore members to extend across any depression there may be in the body of the wearer between the hip bone and the waist line and to be spaced therefrom, as is clearly indicated in Fig. 3 of the drawing.

It will be understood that in the preferred form of my invention, as herein shown and described, the side gore members may be made in one piece and suitably reinforced at or approximately at the waist line by a suitably curved reinforcing strip for accomplishing the same purpose, without departing from the nature and spirit of my invention.

I claim as my invention:

1. In an apparel corset and in each corset body half thereof, spaced stay members, and means between the spaced stay members whereby a portion of the corset body half is caused to extend across a depression in the body of the wearer and to be spaced therefrom at said depression.

2. In an apparel corset and in each corset body half thereof, gore members placed at the side of the garment and connected together adjacent the waist line so as to cause a portion of these gore members to extend across a depression in the body of the wearer and to be spaced therefrom at said depression.

3. In an apparel corset and in each corset

body half thereof, a gore section placed in the upper side portion of the corset body half and having a convex lower edge, and a gore section placed in the lower side portion 5 of the corset body half and having a concave upper edge, the lower edge of the upper gore section being cut at a different curvature than the upper edge of the lower gore sec-

tion and the said edges of the said gore sections being so connected that a portion of the 10 said gore sections is caused to extend across a depression in the body of the wearer and to be spaced therefrom at said depression.

Signed by me this 3rd day of August, 1916.

DANIEL KOPS.
